UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Original application filed December 29, 1921, Serial No. 525,705. Divided and this application filed November 10, 1922. Serial No. 599,973.

To all whom it may concern:

Be it known that I, EDWARD S. STIMPSON, a citizen of the United States, residing at Hopedale, in the county of Worcester and State of Massachusetts, have invented an Improvement in Warp Stop Mechanisms for Looms, of which the following description, in connection with the accompanying drawings, is a specification, like characters on the drawings representing like parts.

The present invention relates to warp stop mechanisms for looms, and the present application is a division of application Serial No. 525,705, filed December 29, 1921.

Warp stop mechanisms as now generally constructed comprise a series of drop wires normally supported by the warp threads during weaving and when one or more of the warp threads break or become too slack for weaving purposes, the associated drop wire moves from a normal to an abnormal position into the path of means, such as a feeler, to effect loom stoppage. To guide the drop wires in their movements it is now the usual practice to provide each row of drop wires, of which there may be one or more, with a drop wire guide, usually in the form of a bar passed through slots in the drop wires. The introduction of the guide bar through the slots of the drop wires is a tedious operation and is now generally accomplished by stringing the drop wires one after another on the associated guide bar by hand.

One of the objects of the present invention is to facilitate the introduction of a guide bar to its drop wire guiding position or through the slots or guide openings of the drop wires, and an important feature of the present invention consists of a drop wire aligning device which enables the drop wires of a row to be readily brought into alignment with their guide slots positioned for the passage endwise of the associated drop wire guide. This feature of the invention may be advantageously employed in any form of warp stop mechanism for bringing the drop wires of a row into posi-

tion side by side but its utility and advantages are best manifested when the drop wires are provided with elongated openings or slots through which the drop wire guide is to extend.

In accordance with the invention, as shown, the drop wire aligning device is temporarily supported by the warp stop mechanism proper or other convenient support when the parts are in the position they occupy in the loom, and serves to bring the drop wires into alignment side by side for the introduction endwise of the drop wire guides, which may then be secured to the guide supports. The novel features of the invention and new combination of parts will best be made clear from the following description and accompanying drawings showing one good practical form of the invention.

In the drawings:—

Fig. 1 is a prospective view of portions of a warp stop mechanism secured to the loom in the position occupied during weaving, the feeler being omitted for clearness of illustration.

Fig. 2 is a cross sectional view showing the aligning device in the position it occupies for aligning the drop wires.

Fig. 3 is a view similar to that of Fig. 2, but showing the aligning device being applied or renewed.

The general construction of the warp stop mechanism may be of any usual or desired type, but as shown it is substantially like that shown and described in the patent to Edward S. Stimpson No. 1,409,425, March 14, 1922, to which reference may be made for a more full disclosure of one form of warp stop mechanism in connection with which the present invention may be advantageously employed.

The loom frame 1 has connected to each side thereof supports for the warp stop mechanism and, as shown, these comprise brackets 2, one at each side of the loom, having slots 3 to which are adjustably secured the side brackets or supports 4, which,

in the present instance are adjustably connected to the brackets 2 by bolts 5 and slots 6.

The supports 4, one at each side of the loom, constitute the supporting elements for the drop wire guides 7 and the warp supporting rods or bars 8. The number of drop wire guides and warp supporting rods or bars may be varied to suit conditions of use, but in the present instance four of each are shown.

As described in the application Serial No. 525,705 of which this is a division, the brackets or supports 4 may be connected by a truss frame comprising the upper and lower rails 9 and blocks 10, and the ends of the truss frame may be secured to the supports 4 by bolts 11. The feature of truss frame, however, is not claimed in this application and may or may not be employed in connection with the aligning device, to be described.

The side supports 4 have means for securing the drop wire guides 7 in place, and as shown, such means may be formed of lugs 12 against which the drop wire guides 7 are secured by the clips 13, while the warp supporting rods or bars 8 have their ends sustained in open bearings carried by the side supports 4.

The rock shaft 15 supported in bearings 14 and carrying the feeler actuating arm 16 and the arm 27 and its associated devices for effecting loom stoppage when the feeler is arrested by a drop wire may all be as more fully described in the application of which this is a division, but as such features do not pertain to the aligning device they are not further shown or described herein.

The drop wires 29 consist of metal pieces which may be stamped out of sheet metal or be otherwise formed and each is provided with a guide slot or opening 30. So far as the broad aspects of the invention are concerned, the drop wires 29 may be of any well known type, but as shown, they are of the "hair pin" form, that is, portions of the drop wires are open slotted to form the legs 32. In some cases drop wires of the hair pin type have a hole for the passage of a warp thread, but usually the hair pin drop wire straddles its thread *a* and is supported on the thread at the closed portion at the upper end of the legs. Either type may be employed in connection with the present invention.

As will be seen from Fig. 3, the drop wire guides 7 pass through the slots 30 of the drop wires, that is each row of drop wires 60 has passed through it a drop wire guide, and to align the drop wires of a row for the insertion of the drop wire guide, the present invention provides a drop wire aligning device which is shown in the present instance as formed by aligning members

33 extending between the saddles 34, two of which are shown. The aligning members 33 are constructed and arranged to enter the space between the leg portions 32 of the drop wires, which when supported by the warp threads in the loom, align the drop wires for the endwise insertion of the guide bars.

Each saddle 34 is constructed and arranged as shown to be hung upon some portion of the main warp stop mechanism when such mechanism is in the position it is to occupy in the loom, and for this purpose has a hanger at each end for supporting the aligning device in its drop wire aligning position. In the present instance the hanger 36 has a hooked portion 37, Figs. 2 and 3, which may be conveniently hung upon the rock shaft 15, while the hanger 38 has a portion 40 which may be hung upon the truss frame 9, and each of the hangers 36 and 38 is adjustably connected to the associated saddle by a bolt or thumb screw 35 passed through a slot 39 in each hanger and into the end portions of the saddle that the position of the aligning bars may be properly adjusted for engagement with the drop wires.

In the use of the drop wire aligning device, the hangers 36 and 38 carrying the saddles and aligning bars or rods are hung upon portions of the warp stop mechanism probably while it is in operative position in the loom with the warp threads *a* passing over the warp supports 8. When the drop wires 29 are of the type that are supported by the upper closed end of the open slots forming the legs 32, the drop wires are placed upon the warp threads by inserting the drop wires successively over the warp threads with the lower open or hair pin leg portion of the drop wires engaged with the associated aligning bar, as indicated in Fig. 2. The effect of this is that all the drop wires of a row are held in alignment side by side with their slots 30 positioned for the endwise introduction of the associated drop wire guide 7. If it were not for the aligning device, the drop wire, when hung upon the warp threads, would fall or turn about the warp threads as centers and require to be turned back by hand one by one to allow the insertion of the drop wire guide. This is true whether the drop wires are hung upon the warp threads, as in the present instance, or have the warp threads passed through eyes formed in the drop wires.

After the drop wire guide 7 has been passed through the guide slots of the aligned drop wires, it is secured to the end supports 4 by the clips 13 or other appropriate means, and the drop wire aligning device may then be detached or remain in place as desired.

It will be apparent that the assembly of the drop wires and drop wire guides is greatly facilitated by the drop wire aligning device even when the parts of the warp stop mechanism are in operative position.

The feeler carrier, the feelers 47 and other features of the warp stop mechanism not claimed herein are consequently not described as they are or may be the same as in 10 the application of which this is a division.

Claims:

1. In a warp stop mechanism for looms, the combination of a series of drop wires, drop wire guides for guiding the drop wires of a row, supports at each side of the loom forming a permanent part of the stop mechanism and unobstructed for the endwise introduction of the drop wire guides, and a drop wire aligning device for 15 aligning the drop wires of a row between the supports in the position relative thereto that they occupy during weaving that the drop wire guides may be introduced endwise into its supports and also in guiding 20 relation to the aligned drop wires.

2. In a warp stop mechanism for looms, the combination of a series of drop wires, a drop wire guide, brackets secured at each side of the loom having unobstructed 25 supports for the endwise introduction of the drop wire guide into said supports, and an aligning device for aligning the drop wires of a row between the brackets in the position they occupy relative thereto during 30 weaving that the drop wire guide may be introduced endwise to its supports and into guiding relation with the aligned drop wires while the latter are retained in weaving 35 position.

3. In a warp stop mechanism for looms, the combination of a series of drop wires having guide slots, a drop wire guide, brackets secured in position at each side of the loom and having supports for the drop 40 wire guide which are unobstructed for the endwise introduction of the guide, and a device for aligning the drop wires of a row between the brackets in weaving position that the drop wire guide when introduced 45 endwise into its permanent guiding position may be inserted through the guide slots of the aligned drop wires while the latter are retained in weaving 50 position.

4. In a warp stop mechanism for looms, the combination of a series of drop wires having guide slots, a drop wire guide, brackets at each side of the loom forming a permanent part of the warp stop mechanism and having unobstructed supports for 55 the endwise introduction of the drop wire guide, and a drop wire aligning device mounted to align the drop wires of a row in weaving position between the brackets with the guide slots of the drop wires in 60 line with the unobstructed supports for the 65

drop wire guide that the latter may be passed endwise to its permanent support and through the guide slots of the aligned drop wires while the latter are retained in this position.

5. In a warp stop mechanism for looms the combination with drop wires and a drop wire guide, of a drop wire aligning device, comprising an aligning bar for engagement with the drop wires of a row when the drop wires are supported on the warp threads in the position they occupy during weaving and for lining-up the drop wires side by side for insertion of the drop wire guide through the drop wires while they are held in said weaving position, and brackets for supporting the aligning bar for removal from operative position when the drop wire guide has been engaged with the row of aligned drop wires.

6. In a warp stop mechanism for looms, the combination of brackets supported at each side of the loom, hangers supported from the brackets, a series of drop wires having guide slots and adapted to be strung upon the warp threads between the brackets, an aligning bar mounted on the hangers for aligning the drop wires of a row, and a drop wire guide adapted to be inserted endwise through the guide slots of the aligned row of drop wires and while the drop wires are held in weaving position.

7. In a warp stop mechanism for looms, the combination of two brackets, one at each side of the loom, a series of drop wires, a drop wire guide for guiding the movements of the drop wires during weaving, a drop wire aligning device constructed and arranged for bringing the drop wires of a row into alignment side by side between the two brackets and in the position they are to occupy during weaving for the endwise insertion of the drop wire guide into the row of aligned drop wires, and means for supporting the drop wire aligning device in drop wire aligning position.

8. In a warp stop mechanism for looms, drop wire guide supports fixed at each side of the loom and unobstructed for the endwise introduction of a drop wire guide, a drop wire guide adapted to be sustained by said supports in drop wire guiding position, an aligning device for aligning the drop wires of a row for engagement by the drop wire guide as the guide is inserted endwise into the fixed supports at each side of the loom, and means for supporting the drop wire aligning device for removal from drop wire guiding position after the row of aligned drop wires have been engaged by the drop wire guide.

9. In a warp stop motion for looms, the combination of two brackets, one at each side of the loom, a drop wire guide adapt-

ed to be supported by the brackets in drop wire guiding position, an aligning device constructed and arranged to engage and align a row of drop wires between the two
5 brackets in the position they occupy during weaving, and drop wire guide bearings supported by the side brackets and constructed

to permit the drop wire guide to be inserted through a row of drop wires while the latter are aligned between the brackets in said 10 weaving position.

In testimony whereof, I have signed my name to this specification.

EDWARD S. STIMPSON.
